COUNTING MACHINE

Patrick M. McDavid, Fort Worth, Tex.

Application August 3, 1950, Serial No. 177,494

5 Claims. (Cl. 101—301)

1

This invention relates to counting machines and more particularly to a machine for counting timing lines on records.

While this invention is applicable to counting timing lines on records in general, for the sake of clarity and simplicity it will be described herein in connection with counting the timing lines on oscillograph records, e. g. as produced in a seismograph camera.

Heretofore in counting the timing lines on oscillograph records the general practice has been to count the lines by hand, beginning at a predetermined zero line on the record and writing consecutive numbers on each tenth line thereafter. Hand counting is unsatisfactory in that the practice is slow and inaccurate as to locating each tenth line and also as to properly numbering said lines. Furthermore, the legibility of the pen-and-ink numbering of the lines depends on the penmanship and care of the particular operator, and consequently is often difficult or impossible to read.

An object of this invention is to provide a counting machine. Another object is to provide a machine for counting timing lines on records. A further object is to provide a machine for counting timing lines on records, which machine eliminates the disadvantages of the prior art. A still further object is to provide a machine for counting timing lines on records, which machine is characterized by accuracy, by speeding up the process of counting the lines, by producing good results, and by simplicity of construction and operation. Other objects will be apparent from the description of this invention given herein-after.

The above objects are accomplished according to this invention broadly by providing and employing a machine which comprises in combination: a base and top pivotally attached together along one side thereof, an elastic member on said top, a series of characters on the elastic member spaced apart a predetermined distance, means for inking the characters, means for adjusting the elastic member and maintaining it in substantially the condition to which adjusted.

A preferred embodiment of this invention will now be described in more detail with reference to the accompanying drawings. Like reference numerals are used to indicate identical parts.

Referring to the drawings generally:

Figure 1 is a pictorial view of the machine, showing the general overall picture of the machine with the top and shelf open and a record in the machine in position to be counted by closing the top.

2

Figure 2 is a side elevation of the machine, showing the characters being inked.

Figure 3 is a side view of the machine as it appears when counting the lines of a record.

Figure 4 is a plan view in broken-out section, showing the spool and shaft for adjusting the elastic member.

Figure 5 is a side elevation of Figure 4.

Figure 6 is a sectional view along the line A—A 10 of Figure 1, showing details of one of the clamps for clamping the elastic member to the top of the machine.

Figure 7 is an end view showing details of the counterbalance spring which can be used 15 to facilitate opening the top of the counting machine.

Referring to the drawings in greater detail:

The machine according to a preferred embodiment of this invention comprises the following:

20 A base 1 and top 2 are pivotally attached together, e. g. as by hinges 3, along one side thereof. An elastic member 4, e. g. rubber or other elastic material in the form of a band or strip, extends along the upper side of the outer free edge opposite the hinged edge of the top. One 25 end of the elastic band 4 is attached to the top 2 at one corner thereof and the other end is attached to a spool 5 on the opposite corner of the top. The spool is rotatably mounted on a shaft 6. The shaft 6 is secured to the top 30 by means of a metal or other suitable strip 7 which is fastened to the top 2 by means of screws 8 or other suitable fastening means.

One example of records of the type under 35 consideration is the type record made by an oscillograph camera. The distance between lines on such records varies from one type of record to another type of record, from one record to another record of the same type, and also within any given record. The records also have longitudinal parallel lines crossing the transverse lines at right angles, although only the transverse lines are counted. In view of this and the requirement that the numbers or other characters used 40 to count the lines on records must fall on or index with the lines to be counted, the distance between the characters must be extremely flexible or otherwise the counting machine will be so restricted in use as to be practically worthless.

50 A series of characters 9 are secured to the elastic band 4. These may be attached to the bend by gluing or otherwise. Usually each character is a piece of metal, plastic, rubber or other satisfactory material having a number thereon, and the numbers are in consecutive

order reading from left to right on the elastic band 4 as it appears on the machine. Generally the characters are placed an equal distance apart on the band, the spacing corresponding as near as possible to the minimum distance between the lines to be counted on records in general. The distance between the characters 9 is increased uniformly by turning the spool 5 counter-clockwise, causing the elastic band 4 to wind upon the spool 5 and uniformly stretch the band. Locking means, e. g. a friction washer 10, prevents the spool from turning back in a clockwise direction to its initial position and thereby holds the band in substantially the condition to which stretched.

This adjustment means alone would be sufficient if the distance between lines in a given record were uniform, but since they are frequently non-uniform, other means of adjustment must be provided so that the band can be in effect divided into segments or sections and the distance between characters within a given segment can be uniformly adjusted independently of another segment. The preferred means of making such adjustment is provided for by clamps 11 and 11-a attached at intervals to the top 2 of the machine. Any number of clamps desired may be provided, and of those provided any number or none may be used on a given operation, depending on the variance encountered in a record.

After counting a record, usually the elastic band 4 is under tension (i. e. stretched) and is held under such condition by the friction washer 10 and the clamps 11 and 11-a. It is desirable not to alter this condition except when and as required for counting the next record, because counting this next record usually will require that the band be under tension which may be the same or different from that required in counting the previous record. Generally it has been found that following this practice saves time as compared with releasing the band to its normal unstretched condition after counting each record. For this reason reference herein to "adjusting" the elastic band is intended to include stretching the band to increase the distance between the characters thereon, or lessening the tension (under which the band happens to be at the time adjustment is begun) to decrease the distance between the characters.

Although various other clamping devices may be employed, the preferred clamp is shown in Figure 1 and Figure 6 of the drawings. This clamp includes a regular bolt 12, a piece of spring steel 13 on the head of the bolt, a slotted wedge 14, a washer 15 and nut 16. Excellent results have been obtained with a flat spring steel turned inwardly toward the elastic band 4, the turned-in edge 17 being serrated 18 e. g. as on the cutting edge of a saw blade, to give increased gripping effect. The bolt passes through a hole in the top 2 of the machine so positioned that the serrated edge of the spring can grip the elastic band. The slotted wedge 14 is on the opposite side of the top. As the thicker part of the wedge is pushed beneath the washer 15, the serrated edge 18 of the spring 13 firmly grips the elastic band 4 against the top of the machine and thereby in effect divides the elastic band into segments, three segments 19, 20 and 21 being possible with two clamps. As the thinner part of the wedge is pushed beneath the washer 15, the spring releases its grip on the elastic band.

A shelf 22 is pivotally attached, as by hinges 23, to the side of the base 1 opposite the side on

which the top 2 is hinged. Along one surface the shelf has attached thereto an absorbent material 24 (Figure 3) e. g. balsawood, adapted to hold ink for inking the characters 9 when the shelf is in a closed position. Figure 2 shows the characters being inked in this manner. When the shelf is in an open position (Figure 1), under certain circumstances it serves as a support for a record being counted, as will be pointed out hereinafter in describing the operation of the machine.

A record 25 is shown in Figure 1 in position to be counted. Arms 26, e. g. of flat spring steel, at both ends of the base 1 hold the record in place while being counted. A mirror 27 enables the operator, while seated at about the center of the machine, to index the zero line of the record with the zero line 28 of the machine. A counterbalance spring 29 may be provided if desired to facilitate opening the top 2.

The operation of the machine just disclosed will now be described with reference to counting the timing lines on an oscillograph record made with a seismograph camera. It is general practice in counting these records, first to select the zero line on the record and designate it by the numeral zero. This is done by selecting some predetermined line near the shot break, which is a break on one of the longitudinal lines of the record and represents the time of explosion of the detonator cap used in the seismic prospecting operation. The line selected as zero depends, among other things, upon the method of computing the record, as is clearly understood in the art. Next each tenth timing line on the record is counted, using the numeral 1 for the first timing line and consecutive numerals for the timing lines to be counted that follow. Usually each tenth line is somewhat darker than the lines in between. Since the lines are close together, it is important that each number fall on the corresponding line counted. Because of the inherent variables in the operation of the seismograph camera (and like high speed cameras in this respect) and the variance between such cameras, the spacing of the timing lines almost always varies from record to record and frequently varies within a given record. Thus the distance between ten timing lines in one part of a record is often greater or less than the distance between ten timing lines in another part of the same record.

In operating the counting machine of this invention, the shelf 22 is closed by folding it back upon the top surface of the base 1, as shown in Figure 2. This brings the absorbent material or inking pad 24 in alignment with the characters 9 on the elastic band 4 when the top 2 of the machine is closed. The top of the machine is closed, thus inking the characters. Normally it is sufficient to ink the characters after about every fifth use. The shelf is then opened to the position shown in Figure 1. A record 25 is placed in the machine by slightly raising the spring arms 26, slipping the record under them, indexing the zero line of the record with the zero line 28 of the machine, and then releasing the spring arms to hold the record in place.

Next the characters 9 must be indexed with the timing lines on the record to be counted. If the distance between lines on the record is substantially uniform, indexing is relatively simple and the clamps 11 and 11-a are not necessary. In such case counting is done by closing the top 2 such that the characters 9 are slightly above the

timing lines and then turning the spool 5 until any one character is indexed with a timing line to be counted. Since in this particular part of the description the characters 9 are being indexed with the timing lines uniformly spaced apart on a record, and since the characters are uniformly spaced apart, it will be readily seen that by indexing one character with one timing line the remaining characters will be indexed with the remaining timing lines. The friction washer 10 holds the elastic band 4 in the position to which adjusted. The top 2 is pressed against the base 1, thereby numbering the timing lines of the record. These numbers will appear on the outside edge of the record with respect to its position in the machine. If it is desired to count the opposite edge of the record 25, the spring arms 26 are again raised and the record moved toward the operator over the shelf 22, the zero lines of the record and machine indexed as before, the spring arms released and the top 2 closed. In counting this edge of the record, the shelf serves as an extension of the base 1 of the machine and aids the base in supporting the record 25.

If the timing lines on the record are unevenly spaced, as they are on most records, proper counting requires additional adjustments of the machine, and the clamps 11 and 11-a, or equivalent means, become a necessity. In counting such unevenly spaced lines, the characters 9 are inked, if needed, and the record positioned, as described above. The characters on the first segment 19 of the elastic band 4 (i. e. the characters between the mirror 27 and the first clamp 11) are indexed with the corresponding part of the record 25. This is done, as described above, by partially closing the top 2 and then turning the spool 5 until the characters are in alignment with the timing lines to be counted. The clamp 11 is set, as described above, thereby binding the elastic band to the top 2 and maintaining this segment 19 of the band in the position to which adjusted. Segment 20 and segment 21 of the band are adjusted in like manner using the clamp 11-a and spool 5. After indexing is complete, the record is counted by closing the top.

Alternatively, instead of the shelf 22 and inking pad 24 thereon for inking the characters 9 prior to use, an arrangement may be used similar to that used on a typewriter for inking the type. For instance, the inked ribbon and spools therefor of a conventional typewriter, or equivalent means, can be suitably mounted on the top 2 of the machine such that the ribbon extends over the characters 9 and counts the record by typewriter action when the top 2 is closed. The point at which the characters contact the ribbon can be changed simply by turning the spool and winding the ribbon onto one spool off the other spool. While this alternative is contemplated and within the scope of the present invention, it does not work as well as the preferred embodiment described hereinbefore. One difficulty is that the inked ribbon tends to smear on the record and the numbers so placed on the record tend to be blurred. While the inking means described above prior to this paragraph is preferred to the ribbon inking means just described, the two inking means are substantially equivalent for the purposes of this invention.

While clamps 11 and 11-a which are non-adjustable (as shown in the drawings) lengthwise of the machine are preferred, these clamps may be made adjustable by providing elongated slots

in the top 2 of the machine and placing the clamps in the slots.

The arms 25 which hold the record in place may be raised directly by hand, or they may be raised remotely by means (not shown) of a foot pedal arrangement having suitable connections to the arms.

As many apparently widely different embodiments of this invention may be made without departing from the spirit and scope thereof, it is understood that the invention is not to be limited to specific embodiments thereof except as defined in the appended claims.

I claim:

1. A machine for counting timing lines on records, comprising in combination: A base and top pivotally attached together along one side thereof; an elastic member along the inside surface of the top, a series of characters on the elastic member spaced apart a predetermined distance, means for inking the characters including an absorbent material secured to a backing or support therefor pivotally attached along the opposite side of said base, means for adjusting the tension in the elastic member and thereby varying the distance between the characters, means to maintain the elastic member in substantially the condition to which adjusted, means for clamping the elastic member against said top and thereby dividing the elastic member into a number of segments; a mirror for aiding in positioning the record on the machine, and means for holding the record in place on the machine.

2. A machine for counting timing lines on records, comprising in combination: a base and top hinged together along one side thereof; an elastic member on said top; a series of characters on the elastic member substantially equally spaced apart a predetermined distance; a shelf hinged along the opposite side of said base; an absorbent material attached to and extending along the shelf for inking the characters; means for adjusting the elastic member and thereby varying the distance between the characters; locking means to maintain the elastic member in substantially the condition to which adjusted; clamping means on said top adapted to clamp the elastic member against said top and thus divide the elastic member into segments which may be adjusted uniformly to a different degree to vary the distance apart of the characters of one segment over that in another segment in order that the characters will index with the lines on the record to be counted, thereby providing a machine for accurately and rapidly counting the timing lines on a record in which the distance between timing lines varies.

3. A machine for counting timing lines on records, comprising in combination: a base and top hinged together along one side thereof; an elastic member on said top; a series of characters on the elastic member substantially equally spaced apart a predetermined distance; a shelf hinged along the opposite side of said base; an absorbent material attached to and extending along the shelf for inking the characters; means, including a spool rotatably mounted on a shaft attached to said top, one end of the elastic member being attached to the spool, for adjusting the elastic member and thereby varying the distance between the characters by rotating the spool around the shaft; locking means, including friction washers on the shaft, for maintaining the elastic member in substantially the condition to which adjusted; clamping means on said top

adapted to clamp the elastic member against said top and thus divide the elastic member into segments which may be uniformly adjusted to a different degree to vary the distance apart of the characters in one segment over that in another segment in order that the characters will index with the lines on the record to be counted, thereby providing a machine for accurately and rapidly counting the timing lines on a record in which the distance between timing lines varies.

4. A machine for counting timing lines on records, comprising in combination: a base and top hinged together along one side thereof; an elastic member having its ends attached to said top; a series of characters on the elastic member substantially equally spaced apart a predetermined distance; a shelf hinged along the opposite side of said base; an absorbent material attached to and extending along the shelf, and appearing on the top surface of the shelf when the shelf is in a closed position, for inking the characters by closing the shelf and then closing said top; means, including a spool rotatably mounted on a shaft attached to said top, one end of the elastic member being attached to the spool, for adjusting the elastic member and thereby varying the distance between the characters by rotating the spool around the shaft; locking means, including friction washers on the shaft, for maintaining the elastic member in substantially the condition to which adjusted; clamping means on said top adapted to clamp the elastic member against said top and thus divide the elastic member into segments which may be uniformly adjusted to a different degree to vary the distance apart of the characters in one segment over that in another segment in order that the characters will index with the timing lines on the record to be counted, thereby providing a machine for accurately and rapidly counting the timing lines on a record in which the distance between timing lines varies.

5. A machine for counting timing lines on records, comprising in combination: a base and top hinged together along one side thereof; an elastic member having its ends attached to said

top; a series of characters on the elastic member substantially equally spaced apart a predetermined distance; a shelf hinged along the opposite side of said base; an absorbent material attached to and extending along the shelf, and appearing on the top surface of the shelf when the shelf is in a closed position, for inking the characters by closing the shelf and then closing said top; means, including a spool rotatably mounted on a shaft attached to said top, one end of the elastic member being attached to the spool, for adjusting the elastic member and thereby varying the distance between the characters by rotating the spool around the shaft; locking means, including friction washers on the shaft, for maintaining the elastic member in substantially the condition to which adjusted; clamping means on said top adapted to clamp the elastic member against said top and thus divide the elastic member into segments which may be uniformly adjusted to a different degree to vary the distance apart of the characters in one segment over that in another segment; a mirror for aiding the operator in properly placing the record on the machine; and means for holding the record in place on the machine, thereby providing a machine for accurately and rapidly counting the timing lines on a record in which the distance between timing lines varies.
